UNITED STATES PATENT OFFICE.

BABETTE BECKWITH AND REUBEN BECKWITH, OF SAN FRANCISCO, CALIFORNIA.

DESIGN FOR A CIGARETTE HOLDER.

Application filed June 17, 1924. Serial No. 9,888. Term of patent 3½ years.

To all whom it may concern:

Be it known that we, BABETTE BECKWITH and REUBEN BECKWITH, citizens of the United States of America, residing at San Francisco, in the county of San Francisco and State of California, have invented a new, original, and ornamental Design for Cigarette Holders, of which the following is a specification, reference being had to the accompanying drawing, forming a part thereof.

We claim:

The ornamental design for a cigarette holder, as shown.

BABETTE BECKWITH.
REUBEN BECKWITH.
